UNITED STATES PATENT OFFICE.

CHARLES A. CARSCADIN AND GEORGE A. WOODMAN, OF CHICAGO, ILLINOIS.

UNCOUPLING DEVICE.

1,141,612

Specification of Letters Patent.

Patented June 1, 1915.

Application filed January 31, 1914. Serial No. 815,658.

To all whom it may concern:

Be it known that we, CHARLES A. CARSCADIN and GEORGE A. WOODMAN, citizens of the United States, both residing at Chicago, in the county of Cook and State of Illinois, have jointly invented certain new and useful Improvements in Uncoupling Devices, of which the following is a specification.

Our invention relates to improvements in uncoupling devices of that class which are mounted on railway cars and the like and which are adapted to be operated to release the locking pin of the coupler without requiring the brakeman to go between the cars.

Numerous uncoupling devices constructed prior to our invention have incorporated in their construction a number of links, clevises and the like, which have been more or less easily removed by farmers, teamsters and others having use for these parts. These devices have also been the source of further inconvenience as the flexible connection thus provided between the operating rod and the locking pin has frequently become jammed or displaced and the efficiency of the device thereby materially impaired. Our invention aims to overcome these disadvantages and provide an uncoupling device, the parts of which will be interlocked each with the others, so that removal of any of them without disconnecting the entire uncoupling device from the car will be impossible and which parts shall be so constructed and arranged that they will not become displaced or jammed in service.

A further object of our invention is the provision of an uncoupling device, the parts of which may be cheaply constructed and readily assembled.

Other objects and advantages of our invention will be apparent from the following description as it is better understood when taken in connection with the accompanying drawing illustrating a preferred embodiment thereof.

On the drawing, Figure 1 is a partial top plan view of a car to which an uncoupling device embodying our invention is secured; Fig. 2 is a front elevation of the uncoupling device and a portion of the end of the car shown in Fig. 1; Fig. 3 is an end elevation of the same; Fig. 4 is an enlarged front elevation of the member provided to secure the locking pin to the operating rod; Fig. 5 is an end elevation of the same, Fig. 6 is

a section taken substantially on the line 6—6 of Fig. 4, and Fig. 7 shows a somewhat slightly modified form of connecting member.

The embodiment of our invention disclosed in the drawing consists primarily of an operating rod 10, an outer bracket 11, an inner bracket 12 and a member 13 provided to connect the operating rod with the locking pin 14 of the coupler 15. In the present instance the operating rod consists of a main body portion 16 which is carried by the brackets 11 and 12 and formed at one end to provide an operating arm 17 and at the other end to provide a lifting arm 18 which is offset by an inclined portion 19 from the main body portion 16. The main body portion 16 of the operating rod is secured adjacent and across the end of the car by brackets 11 and 12 and the portion 19 connecting the lifting arm to this main body portion extends downwardly and outwardly from the car to dispose the lifting arm directly above the locking pin of the coupler 15 and at right angles to the longitudinal axis of the car. The lifting arm is preferably disposed horizontally or substantially horizontally and the locking pin 14 is connected to it by the connecting member 13 which, as will be later explained, slidably embraces this lifting arm. In the present instance this member 13 consists of a rod of iron, steel or other suitable material bent upwardly, as shown in Figs. 4, 5 and 6, at each end of a central portion 22. Each of the upwardly bent portions 23 and 24 thus provided are preferably formed to slidably embrace the lifting arm 18 of the operating rod, one of these portions being bent to provide a closed eye 25 through which the lifting arm is threaded and the other a hook 26 bent to fit nicely over this arm. The extremity of the lifting arm 18 is upturned at 27 to prevent the connecting member 13 from being disconnected therewith. If desired both upwardly extending portions may be bent to provide hooks 26', as seen in Fig. 7, which will effectively prevent the disconnection of the parts as there must be too slight angular relative movement between the rod and connecting member to permit disconnection of the hooks from the lifting arm.

When the parts are assembled the hook 26 of the connecting member 13 is first threaded through the eye of the locking pin and the

2
 upturned end 27 of the operating rod inserted through the eye 25 of the connecting member. The lifting arm 18 is engaged in the hook 26 and the operating rod secured 5 by the brackets to the car. One of these brackets, preferably the inner one 12, is made extensible and in the present instance consists of a pair of outwardly extending arms 28 carrying between them a horizontally 10 movable slide 29 provided with a slot 31 through which the operating rod is disposed. The opening in the other or outer bracket 11 is of sufficient size to permit the operating rod to swing about it as a center when the 15 coupler head moves longitudinally of the car in-service.

The movement of the coupler head transversely of the car body, as occurs when the cars travel around curves in the road, is permitted by the sliding connection between the 20 lifting arm and the connecting member 13 in part and in part also by the horizontal movement of the operating rod, the component of the swinging movement of the 25 coupler head transversely of the car being permitted by the connection between the operating rod and the connecting member and the component of this movement longitudinally of the car by the extensible connection between the rod and the car.

It will be manifest that having once been assembled the member 13 can not be disconnected from the lifting arm of the operating rod without first removing the locking 35 pin from the coupler head or without first removing the operating rod from the car body. All of the parts are thus interlocked and impossible of removal without disconnecting the entire device from the car or the 40 locking pin from the coupler.

The device is simple and cheap in construction and may be readily assembled and operated.

It will be obvious that various changes 45 may be made in the form, construction and arrangement of the parts without departing from the spirit or scope of the invention or sacrificing any of its material advantages, the form hereinbefore described being merely 50 a preferred embodiment thereof.

We claim:

1. An uncoupling device for railway cars comprising an operating rod adapted to be secured to a car, and a rigid member passing through the eye of the locking pin of 55 the coupler and having its opposite ends looped about said rod and slidably longitudinally thereof.

2. An uncoupling device for railway cars comprising an operating rod, means for slidably securing said operating rod to the car to permit movement of said rod longitudinally of the car, and means connected to the locking pin of the coupler having its opposite ends looped about said rod and slidably 60 connected to said rod to move transversely of the car.

3. An uncoupling device for railway cars comprising an operating rod adapted to be secured to a car and having a lifting arm offset 70 from the body portion of said rod and disposed substantially horizontally and at right angles to the longitudinal axis of the car, and a member engaging the locking pin of the coupler at its center and slidably embracing said lifting arm at its ends.

4. An uncoupling device for railway cars comprising a rod adapted to be secured to a car and provided with a horizontally disposed lifting arm, and a rigid member disposed through the locking pin of said coupler and having an eye at one end and a hook at the other, said eye and said hook 80 slidably embracing said lifting arm.

5. An uncoupling device for railway cars 85 comprising an operating rod secured to a car and provided with an integral lifting arm offset from the body portion of said rod disposed substantially horizontally and at right angles to the longitudinal axis of the car, a rigid member embracing said rod with both 90 ends and disposed through the eye of the locking pin of the coupler, said rod being upturned at its end to prevent disengagement of said rod and member.

CHARLES A. CARSCADIN.
GEORGE A. WOODMAN.
